UNITED STATES PATENT OFFICE.

WILLIAM H. ARMSTRONG, JAMES M. PUGH, AND ROBERT W. MAGEE, OF INDIANAPOLIS, INDIANA, ASSIGNORS TO WM. H. ARMSTRONG & COMPANY, OF INDIANAPOLIS, INDIANA, A CORPORATION OF INDIANA.

INVALID-BED.

No. 824,057.

Specification of Letters Patent.

Patented June 19, 1906.

Application filed January 23, 1905. Serial No. 242,275.

To all whom it may concern:

Be it known that we, WILLIAM H. ARMSTRONG, JAMES M. PUGH, and ROBERT W. MAGEE, of Indianapolis, county of Marion, 5 State of Indiana, have invented a certain new and useful Invalid's Bed; and we do hereby declare that the following is a full, clear, and exact description thereof, reference being had to the accompanying drawings, in which 10 like numerals refer to like parts.

The object of this invention is to provide an invalid's bed whereby the patient may be readily elevated above the mattress for any purpose without disturbing him or the bed-clothing in the least and supporting him in such elevated position for any desired length of time, changing the sheets, and easily lowering him upon the mattress. This object is attained by placing strong sheeting or canvas on a mattress and securing it at its edges to a frame and then providing means in connection with the bedstead for elevating said frame and holding the same in an elevated position, whereby said sheeting and patient 25 are elevated above the mattress. This enables the patient to be served in any desired way.

The full nature of the invention will be understood from the accompanying drawings 30 and the following description and claims.

In the drawings, Figure 1 is a perspective view of a bedstead with a mattress on it and said sheeting and frame maintained in an elevated position. Fig. 2 is a plan view of the bedstead with the mattress and the sheeting-frame removed. Fig. 3 is a longitudinal vertical section of the entire construction, as shown in Fig. 1, on the line 3 3 of Fig. 2. Fig. 4 is a plan view of the actuating portion of 35 the shaft. Fig. 5 is a central vertical section 40 along one of the clamping cross-rod.

In detail the drawings herein show an iron bedstead of the usual form and construction and having the side rails 10, the end rails 11, 45 the corner-posts 12, the posts at each end being connected integrally with the top. Upon said bedstead there is a wire mattress 13 and a cotton mattress 14, both of the usual character. The parts so far described may be 50 made in any desired way. An iron frame 15 is provided that fits snugly between the ends of the bedstead and is of about the same width as the frame of the wire mattress. At

the foot and the head said frame carries an antifriction-roller 16, that runs in a grooved 55 vertically-disposed guide-bar 17, secured about midway of each end of the bed to the end rail 11 and the top. This is for the purpose of guiding the vertical movement of said frame 15 and also helping to prevent its lateral displacement. Upon said iron frame 15 sheeting 18 of any sufficiently-strong material, such as canvas, is secured stretched. A head-rest is added to this construction consisting of the iron frame 19, pivoted at 20 to 60 the sides of the frame 15 and supported by braces 21, that at the lower ends engage notches in a toothed bar 22, secured to the frame near the head of the bedstead. A head-rest 23, consisting of strong sheeting or 65 canvas, is stretched on the frame 19. This head-rest may be adjusted to any desired position of elevation. In normal condition the sheeting 18 rests upon the mattress and the patient upon the sheeting. The patient and 70 the sheeting are elevated above the mattress by the following means: A shaft 25 is mounted in brackets 26, one secured to each side rail of the bedstead about midway. Said shaft carries a gear-wheel 27 and is actuated by a 75 toothed wheel 28, pivotally mounted to one side rail of the bedstead in meshing condition with the gear 27, and has secured to it a crank 29 for actuating said toothed wheel 28 and gear-wheel 27 and shaft. Back action of 80 said parts is prevented by the pawl 30, pivoted to one side rail of the bedstead in position to engage the gear 27 and so mounted and formed as to be actuated by gravity and yet be readily releasable.

Under each end of each side rail there is secured a guide-bar 32, so that the oppositely-placed guide-bars will form pairs, one pair near the foot and one pair near the head. Within said guide-bars rods 33 are placed 85 loosely, with both ends protruding somewhat beyond the side rails of the bedstead. Upon said protruding ends the supporting-bars 34 are mounted. Said bars are pivoted at their upper ends to the sides of the frame 15. The rods 33 at one side of the bed have heads 35 on them and at the other side of the bed are threaded, as shown in Fig. 5, to receive the clamping-nut 36, having a handle.

To each rod 33 near each end under the 105 bed and between the side rails a push-bar 38

is pivoted. Clamping sleeves or tubes 37 are placed loosely on said rod 33 between the lifting-bars 34 at each end and the push-bars 38, and also between said push-bars, so that 5 there are three of said clamping-tubes or three sections for each rod 33. Said push-bars at their other ends are looped around a gear-wheel 40, that is secured on the shaft, and on one side of the loop there is a rack 41. 10 On each side of each gear 40 there is a collar 42 of larger diameter than the gear and wider than the loop, so as to hold the loop on the gear and prevent its lateral escape. Hence, as seen in Figs. 2 and 3, the two loops 15 on the two push-bars 38 at each side of the bedstead extend in opposite directions, but ride upon and are actuated by the same gear-wheel 40. The rack 41 is on the lower side of one loop and on the upper side of the other 20 loop of each pair, so that the actuation of said shaft 25 in one direction will simultaneously and equally move the push-bars 38, rods 33, and the lower ends of the supporting-bars 34 toward the ends of the bedstead. 25 This movement will cause the elevation of the frame 15 and sheeting 18, as seen in Fig. 1. When in such elevated position, the pawl 30 will lock the actuating parts; but to make the supporting means effective the clamp-nut 36 on each rod 33 is turned, thus clamping the lower ends of the supporting-bars 34 tightly against the clamping-tubes 37. When the parts are thus clamped and locked, the sheeting 18 will be maintained in its elevated 35 position under a considerable load.

When it is desired to lower the patient, the crank 29 is held firmly, the pawl 30 disengaged, and then the frame 15 and sheeting will lower under the load by gravity, too 40 rapid lowering being prevented by counter action of the hand on the crank 29. When the parts are lowered, they will be in the position shown in Fig. 3.

With this construction it is observed that 45 both ends of the sheeting-frame and sheeting will be equally and simultaneously elevated and lowered.

What we claim as our invention, and desire to secure by Letters Patent, is—

50 1. The combination with a bedstead, of a frame to which sheeting is secured, a supporting-bar pivoted at the upper end to said frame at each side near the end thereof, longitudinally-extending guideways connected 55 with the side rails of said bedstead, rods extending under the bedstead and loosely

through said guideways with the ends protruding and pivotally mounted in connection with the lower ends of said supporting-bars, and means for moving said rods simultaneously toward the ends of the bedstead. 60

2. The combination with a bedstead, of a frame to which sheeting is secured, a slotted supporting-bar pivoted at the upper end to said frame at each side near the end thereof, longitudinally-extending guideways connected with the side rails of the bedstead, rods extending through the bedstead and loosely through said guideways with the ends protruding through the lower ends of said supporting-bars, means for moving said rods simultaneously toward the end of the bedstead, one end of each of said rods being threaded, clamping-tubes on said rods and a clamping-nut mounted on the threaded end 70 of each rod for clamping the lower ends of said supporting-bars against the clamping-tubes. 75

3. The combination with a bedstead, of a frame to which sheeting is secured, a supporting-bar pivoted at the upper end to said frame at each side near the end thereof, longitudinally-extending guideways connected with the side rails of the bedstead, rods extending under the bedstead and loosely through said guideways with the ends protruding and pivotally mounted in connection with the lower ends of said supporting-bars, means for moving said rods simultaneously toward the ends of the bedstead, a shaft 80 mounted under the bedstead about midway thereof transversely, means for actuating the same, a gear-wheel on each shaft near each end thereof, and a push-rod pivotally connected with each of said rods near each side 85 of the bed that are provided with loops at their other ends surrounding the gears on said shaft, each loop having a rack for engaging the teeth of said gears on said shaft whereby said push-bars are moved horizontally in opposite directions toward the ends 90 of the bed by the actuation of said shaft. 95

In witness whereof we have hereunto affixed our signatures in the presence of the witnesses herein named.
